UNITED STATES PATENT OFFICE.

RALPH ROMAIN MATTICE, OF PAULLINA, IOWA.

CATCH.

Application filed June 13, 1922. Serial No. 563,010.

To all whom it may concern:

Be it known that I, RALPH R. MATTICE, a citizen of the United States, and a resident of Paullina, in the county of O'Brien and State of Iowa, have invented a new and Improved Catch, of which the following is a full, clear, and exact description.

This invention has relation to a catch or fastener for holding relatively slidable members in a predetermined position or positions, the same being particularly designed for use in connection with sliding doors, gates or other closures of this type.

As an object the invention provides a catch for relatively movable members, sliding closures or the like, which is gravitationally operable to effect its engagement or disengagement upon movement of the closure beyond the predetermined position.

More specifically the invention contemplates a catch for use in connection with vertically slidable closures for the purpose of holding the same in a predetermined elevated position and in which the catch element is gravitationally operable for engagement and disengagement with a keeper upon movement of the closure above the predetermined elevated position.

A still further object is to provide a catch as heretofore set forth which also includes a spring actuated bolt designed to coact with vertically spaced keepers for locking the closure in a lowered or closed position or for holding the same in various intermediate elevated positions between its closed and extreme open position.

The invention furthermore contemplates in connection with a spring actuated bolt of the character described, means for respectively rendering the same active and inactive.

As a further object the invention resides in the provision of a catch of the character set forth which is extremely simple in its construction and mode of operation, which is inexpensive to produce and install, which is of a strong and durable nature, and which is positive and efficient in its action and purpose.

With the above recited and other objects in view, the invention resides in the novel construction set forth in the following specification, particularly pointed out in the appended claims and illustrated in the accompanying drawings, it being understood that

the right is reserved to embodiments other than those actually illustrated herein to the full extent indicated by the general meaning of the terms in which the claims are expressed.

In the drawings—

Figure 1 is a fragmentary front elevation of a vertically slidable closure and support, illustrating the same equipped with a catch constructed in accordance with the invention.

Fig. 2 is a transverse sectional view therethrough illustrating the catch in side elevation.

Fig. 3 is a similar view illustrating the catch in active position for holding the closure in a predetermined elevated position.

Fig. 4 is a similar view illustrating the manner in which the catch is released.

Referring to the drawings by characters of reference, 10 designates a door, gate or other closure which is mounted for vertical sliding movements in the guideway 11 of a support or frame 12.

The catch or means for fastening the closure in a predetermined elevated position or positions includes a vertical guide bar 13 which is disposed parallel to the path of movement of the closure and is preferably supported therefrom by a bracket or brackets 14 which are secured to the support 12.

The guide bar is provided at its forward edge with a keeper notch 15 adjacent its upper end and with subterposed vertically spaced keeper openings 16. The catch element designated generally by the reference character 17 embodies an arm 18 which is pivoted at its lower end as at 19 to a forwardly projecting bearing lug 20 attached to the upper edge of the closure 10. The free upper end of the arm 18 has pivoted thereto as at 21 the inner end of a link 22 which embraces the bar 13. The link consists of spaced side arms 23 and 24 which are connected together at their inner ends by the pivot 21 with the upper free end of the arm 18 interposed therebetween. The outer ends of the side arms 23 are connected together by a transverse rivet 25 and are

spaced apart by a sleeve 26 interposed therebetween and mounted for free rotation on the rivet. Under this arrangement when the closure 10 is moved upwardly, the upper free end of the arm 18 will gravitationally engage and coact with the inner edge of the

2

bar 13 due to the fact that the inner edge of the bar 13 is spaced an appropriate distance in front of the pivot 19 to cause the arm to be disposed at an outward inclination. In this position of the arm 18, the outer end of the link 22 will gravitate downwardly until the sleeve 26 coacts and engages with the outer edge. The keeper notch 15 is provided with a convex rear wall 27 which merges into the semi-circular upper and lower walls 28 and 29 at their upper and lower ends. The lower wall 29 merges into an upwardly inclined edge 30 which terminates in a downwardly and outwardly curved edge 31 which merges into the outer edge of the bar 13. The upper semi-circular wall or edge 28 terminates in a horizontal subterposed edge 32 which is disposed at a right angle to and terminates in line with the edge of the bar 13. When the closure 10 is elevated to a predetermined height, the catch operates in the following manner, the sleeve 26 of the link 22 passes over the downwardly and outwardly curved edge 31 and gravitates over the inclined edge 31 into the lower semi-circular wall 29. At this point further continued upward movement of the closure causes the sleeve 26 to roll over the convex rear wall 27 of the notch until the sleeve engages within the upper semi-circular wall 28 which arrests further upward movement of the closure and acts as a limiting stop therefor. When the closure is released or permitted to move downwardly the sleeve 26 will again roll over the convex rear wall 27 of the keeper notch and will engage within the semi-circular lower wall 29. Further continued downward movement of the closure effects a downward and inward swinging of the inner pivoted end 21 of the link 22, which in turn effects a rearward or inward swinging of the upper end of the arm 18 away from the rear edge of the guide bar 13. As the closure continues to move downwardly the inner pivoted end 21 of the link 22 continues to describe an arcuate path, thus swinging the upper pivoted end of the arm 18 forwardly or outwardly into contact with the rear edge of the bar 13 at which point the closure is positively supported and maintained by the catch in the predetermined elevated position intended. When thus locked or maintained in its predetermined elevated position, the release of the catch is effected in the following manner; the closure is slowly elevated in order to maintain the upper end of the arm 18 in contact with the rear edge of the bar 13. This movement causes the link 22 to be moved upwardly and outwardly, the same being guided in its movement by the passage of the sleeve 26 over the upwardly inclined edge 30. When the sleeve 26 passes the upwardly inclined surface, the outer end of the link 22 gravitates downwardly until the

sleeve engages the forward edge of the bar 13, thus permitting the lowering of the closure.

In order to provide means for locking or retaining the closure in subterposed or intermediate positions between the keeper notch 15 and its lowermost or closed position, one of the side arms 23 of the link is provided with a laterally projecting yoke 33 through the apertured bight 34 of which and an aperture in the side arm 23, a sliding bolt 35 is movable, the inner extremity of which is adapted to engage in the keeper opening 16. A spring 36 is connected with the bolt 35 adjacent its inner end and bears against the inner side of the bight 34 to normally effect the projection of the inner end of the bolt into the keeper openings. The outer side of the bight is provided with a boss 37 through which the outer end of the bolt extends. The bolt is provided with a pin 38 extending therethrough and the boss is provided with diametrically opposed longitudinal slots 39. The outer extremity of the bolt is provided with a knurled head 40 which serves as a means for withdrawing the bolt against the action of the spring 36 to release the same from the keeper opening 16. When it is not desired to employ the bolt, the same is drawn outwardly and turned to withdraw the pin 38 from the slots 39 and engage the same with the outer end of the boss to hold the bolt in retracted position.

I claim:

1. A device for holding a movable member in a predetermined position comprising a guide element disposed parallel to the path of movement of said member, said guide element having a keeper notch, a catch element having a locking portion gravitationally engageable with and disengageable from the keeper notch upon movement of the member beyond said predetermined position.

2. A device for holding a sliding closure in a predetermined open position, comprising a guide element disposed parallel to the path of movement of the closure, said guide element having a keeper notch therein, and a catch element having a locking portion engageable within and disengageable from the keeper notch upon movement of the closure beyond said predetermined open position.

3. A device for holding a vertically slideable closure in a predetermined elevated position, comprising a guide element disposed parallel to the path of movement of the closure, a keeper on said guide element, and a catch element movable over the guide element and having a locking portion gravitationally operable for engagement and disengagement with the keeper upon movement of the closure beyond said predetermined elevated position.

4. A catch for holding a vertically slide-
able closure in a predetermined elevated
position, comprising a vertical guide bar
having a keeper notch in one edge and dis-
posed parallel to the path of movement of
the closure, and a catch element pivoted to
the closure and movable over the bar upon
sliding of the closure, said catch element
having a portion adapted to be gravita-
tionally engaged within the keeper notch
upon elevation of the closure above said
predetermined elevated position and adapt-
ed to be gravitationally disengaged from
said keeper notch upon an initial elevation
of the closure above said predetermined ele-
vated position.
5. A catch for holding a vertically slide-
able closure in a predetermined elevated
position, comprising a vertical guide bar
disposed in parallel relation to the path of
movement of the closure, said guide bar hav-
ing a keeper notch therein, a catch element
comprising an arm pivoted at its lower end
to the closure and normally engaged at its
free upper end with the bar, a link pivotal-
ly connected to said free end and embracing
the bar, and a transverse notch engaging
portion at the free end of the link adapted
to gravitationally engage within the notch
upon movement of the closure beyond its
predetermined elevated position and adapt-
ed to be gravitationally disengaged from
the keeper notch upon an initial upward
movement of the closure beyond its pre-
determined elevated position.
6. A device for holding a vertically slide-
able closure in predetermined elevated posi-
tions comprising a guide element disposed
parallel to the path of movement of the
closure and having a keeper notch in its
edge and subterposed vertically spaced
keeper openings, a catch element movable
over the guide element and having a lock-
ing portion gravitationally operable for en-
gagement and disengagement with the
keeper notch upon movement of the closure
- beyond said keeper notch, a spring actuated
bolt carried by said catch element adapted
to be selectively engaged in the keeper open-
ings, and means for rendering said bolt 50
inactive.
7. The combination with a closure mount-
ed for vertical sliding movement, of means
for holding said closure in a predetermined
elevated position, comprising a guide bar 55
disposed in parallel relation to the path of
movement of the closure, said guide bar hav-
ing a keeper notch in its outer edge, the said
outer edge of the bar at its juncture with
the lower portion of the notch being up-
wardly and inwardly curved, the lower wall
of said keeper notch being defined by a
downwardly and inwardly inclined edge
merging into a lower semi-circular edge, the
rear wall of said notch being defined by a 60
convex or arcuate edge and the upper wall
of said keeper notch being defined by a semi-
circular edge and a horizontal edge merging
into the semi-circular edge and terminating
flush with the outer edge of the guide bar, 70
and a catch element comprising an arm piv-
oted at its lower end to the closure with its
upper end gravitationally engaging the
inner edge of the guide bar, a pair of spaced
arms pivoted at their inner ends to the op-
posite sides of the upper end of the first arm
and embracing the guide bar and a trans-
verse pin extending through the outer end
of the side arms whereby upon upward
movement of the closure beyond the pre-
determined elevated position, the pin at the
outer end of the side arms will gravita-
tionally enter the keeper notch and engage
the upper wall to afford a limiting stop for
the upward movement of the closure and 80
whereby upon subsequent downward move-
ment of the closure said pin will enter the
semi-circular edge of the lower wall for sup-
porting the closure by the connected side
arms and first mentioned arm.

RALPH ROMAIN MATTICE.
